UNITED STATES PATENT OFFICE.

C. L. A. PALMGREN AND ARTHUR H. YOUNG, OF CHICAGO, ILLINOIS.

TIME-CONTROLLED CIRCUIT-CLOSING DEVICE.

No. 870,900.

Specification of Letters Patent.

Patented Nov. 12, 1907.

Application filed February 16, 1907. Serial No. 357,668.

To all whom it may concern:

Be it known that we, C. L. A. PALMGREN and ARTHUR H. YOUNG, both of Chicago, Cook county, Illinois, have invented a new and useful Time-Controlled 5 Circuit-Closing Device, of which the following is a full, clear, and exact description, reference being had to the accompanying drawings, forming part of this specification, in which—

Figure 1 is a front elevation, partly in section of a 10 time-controlled circuit closing device embodying our invention; Fig. 2 is a vertical section of the same; Fig. 3 is a diagram showing the electrical circuits; Fig. 4 is a front elevation of a modified form of relay; and Fig. 5 is a section of the same taken on the line V—V of Fig. 15 4, with the contacts separated.

Our invention is designed to provide means of simple, convenient and reliable character, for the purpose of closing electric circuits at predetermined times; and is more particularly designed to provide means of this 20 character which may be used to advantage for the purpose of actuating whistles or other signals, at certain times.

With this object in view, our invention consists in the combination, with a clock movement having its 25 hour hand arranged to make electrical contact at certain predetermined times, of one or more controlling members driven by the clock movement, and having contact devices which co-operate with the contacts controlled by the hour hand to complete an electric 30 circuit. This circuit includes a suitable relay device which controls a working circuit or circuits.

Our invention also consists in the novel construction, arrangement and combination of parts, all substantially as hereinafter described and pointed out in 35 the appended claims.

Referring to the accompanying drawings, in which we have illustrated one form of apparatus embodying our invention, the numeral 2 designates a suitable case or closure having a clock dial 3, and containing a clock 40 movement of any ordinary character.

4 is the minute hand of the clock carried by the spindle 5, and 6 is the hour hand which is carried by the sleeve 7, said spindle and sleeve being driven through the gear 8 actuated by the usual movement, not shown.

45 9 is an electrical conductor of circular form which is placed adjacent to the outer edge of the dial 3, and is electrically connected with one side of a circuit supplied by battery 10, and including the coils 11 of the magnets of a relay device 12. The conductor 9 is connected at intervals by branch conductors 13 with contact points 14 which project beyond the outer face of the dial, and are secured in insulating plugs 15 seated in openings of the dial. The number and location of the contact points 14 will depend upon the time or 50 times at which the circuit is to be closed. In the draw-

ings, we have shown one of these contacts arranged to be engaged with a contact device 16 carried by the hour hand 6 at 12 o'clock, 12:30 o'clock, 1 o'clock, 4:30 o'clock, 5:30 o'clock, 6 o'clock and 7 o'clock, respectively. The contact device 16 on the hour hand 6 is 60 connected by a conductor 17 with a conductor 18 surrounding the sleeve 7 and engaged by a contact finger 19. The contact finger 19 is electrically connected by conductors 20 with similar contact fingers 21 and 22. The finger 21 makes electrical contact with a conducting ring 23 carried by a gear wheel 24, and the finger 22 makes contact with a similar ring 25 carried by gear wheel 26. The gear wheel 24 is connected by means of gear wheels 27 and 28 with a gear wheel 29 on the sleeve 7, said gear wheels being arranged to cause the 70 wheel 24 to make one complete revolution each twenty-four hours. The gear wheel 26 is driven by a pinion 30 on the shaft of the gear wheel 24, and is arranged to make one complete revolution each seven days. The contact ring 23 is provided with a series of contacts 31 75 which are designed to be engaged by a contact finger 32. The contact ring 25 carries a contact 33 which is arranged to be engaged by a contact finger 34. The two fingers 32 and 34 are connected in series with the reverse side of the battery 10 by a conductor 35. 80

The contact rings 23 and 25 are insulated from their respective gear wheels, as best shown in Fig. 2. The arrangement of contacts carried by these rings will be best understood by reference to Fig. 3 in which the time relations are indicated. Thus it will be seen that 85 the ring 23 has contacts which are arranged to be engaged by the finger 32 at 12 o'clock noon, at 12:30 p. m., at 1 p. m., at 5:30 p. m., 6 p. m., 7 p. m., 12 o'clock night; 1 o'clock a. m., 6 a. m. and 7 a. m.; while the ring 25 has a single contact arranged to engage the finger 34 at 4:30 p. m. Saturday. 90

The relay 12 controls a working circuit 36 in which is placed the actuating or releasing device for the whistle or other alarm to be sounded. When the device is operated in connection with apparatus which requires a comparatively heavy current in the circuit controlled by the relay, I prefer to employ a relay such as is shown in Figs. 4 and 5. In these figures, 38 designates the relay magnet, and 39 an armature carried by a lever 40. The longer arm of this lever carries a 95 contact 41 at each end, and these contacts are arranged to co-operate with contacts 42 which are carried by arms 43. 44 is a spring which is connected to the short arm of the lever 40. 45 is a screw for adjusting the tension of the spring so that the lever 40 and contact 41 will be normally held or balanced in the position shown in Fig. 5. When, however, the circuit is completed in the magnet coils 38, the armature 40 is attracted which brings the contacts 41 and 42 together. As soon as the circuit is broken in the magnet coils, the spring 44 100 105 110 115

causes the contacts to immediately separate, and they are held separated to such an extent as to prevent any possibility of current jumping between them.

The operation will be readily understood. As the contact device 16 carried by the hour hand comes in contact with each of the points 14, the electric circuit is closed at that point, but unless one of the controlling rings 23 or 25 is at this time in such position that the contact finger 32 or 34 is in engagement with one of the contacts 31 or 33, the circuit is not completely closed. If, however, either of the controlling members is in circuit closing position, a complete circuit is made, and the relay magnets are energized to close the working circuit by means of the movement of the relay armature 37. It will be noted that the contacts 16, 19, 21 and 22 are in series with each other, while the contacts 21 and 32 and the contacts 22 and 34 are in multiple relation. Therefore, while the circuit must be closed at the point 16 and also at one of the controlling members in order to complete the circuit, the circuit at each controlling member is closed independently of the other controlling member.

In the particular arrangement illustrated in the drawings, the alarm or whistle will be sounded each day at each of the times indicated on the controlling ring 23, in Fig. 3, and will also be sounded at 4:30 o'clock on Saturday.

It will be understood that the particular arrangement shown is illustrative merely of one application of the invention, and that the particular arrangement of the contacts on the dial and on the controlling members, and the number of controlling members, and the ratio of their driving gears will depend upon the particular

operations to be controlled in any particular case. It is also obvious that the contacts may be made by the 35 minute hand instead of the hour hand, since the circuit is completed only when the controlling member or members are in the proper positions.

Various other changes may be made in the details of construction and arrangement without departing from the spirit and scope of our invention.

What we claim is:—

1. Time-controlled circuit closing mechanism comprising a clock, a normally open electric circuit having contacts arranged to be closed by a hand of the clock at 45 definite times, and a plurality of controlling members geared to the clock work to rotate in different time periods, and contact devices controlled by said members, the contact devices controlled by each member being in series with the contacts controlled by the clock hand, but in 50 multiple with the contacts controlled by the other member or members; substantially as described.

2. The combination of a clock movement, a normally open electric circuit having a plurality of contact devices in the path of movement of a hand of the clock, a co-operating contact device on the hour hand, a controlling member geared to the clock movement to make a complete revolution each twenty-four hours, a second controlling member geared to make a complete rotation each seven days, and contact devices controlled by each of the controlling members, the devices controlled by each member being in series with the contacts controlled by the clock hand, and in multiple with the contacts controlled by the other member; substantially as described.

In testimony whereof, we have hereunto set our hand. 65

CARL A. PALMGREN.
ARTHUR H. YOUNG.
